US00D852837S

(12) **United States Design Patent** (10) Patent No.: **US D852,837 S**
(45) Date of Patent: **** Jul. 2, 2019**

(54)	DISPLAY SCREEN WITH GRAPHICAL USER INTERFACE FOR CLOSED-LOOP MEDICATION DELIVERY	4,231,368 A	11/1980	Becker
		4,265,241 A	5/1981	Portner et al.
		4,300,554 A	11/1981	Hessberg et al.
		4,313,439 A	2/1982	Babb et al.
		4,398,908 A	8/1983	Siposs
(71)	Applicant: Bigfoot Biomedical, Inc. , Milpitas, CA (US)	4,435,173 A	3/1984	Siposs et al.
		4,443,218 A	4/1984	Decant et al.
		4,493,704 A	1/1985	Beard et al.
(72)	Inventors: Bryan Mazlish , Palo Alto, CA (US); Sabine Kabel-Eckes , Mountain View, CA (US); Shannon Sieber , Santa Clara, CA (US); Jeff Boissier , San Jose, CA (US)	4,529,401 A	7/1985	Leslie et al.
		4,681,569 A	7/1987	Coble et al.
		4,749,109 A	6/1988	Kamen
		4,838,857 A	6/1989	Strowe et al.
		4,850,817 A	7/1989	Nason et al.

CLAIM

The ornamental design for a display screen with graphical use interface for closed-loop medication delivery, as shown and described.

DESCRIPTION

FIG. 1 is a front view of a display screen with graphical user interface for closed-loop mediation delivery, showing a first embodiment of the new design;

FIG. 2 shows a second embodiment thereof;

FIG. 3 shows a third embodiment thereof; and,

FIG. 4 shows a fourth embodiment thereof.

The broken line showing of the device illustrates environmental subject matter, and the display screen, and portions of the graphical user interface are included for the purpose of illustrating portions of the article and form no part of the claimed design.
